UNITED STATES PATENT OFFICE

2,281,385

ELECTRIC CIRCUIT BREAKER

Jacques Marie Saint-Germain and Georges Bala-
chowsky, Paris, France, assignors to General
Electric Company, a corporation of New York

Application May 17, 1940, Serial No. 335,828
In France June 22, 1939

5 Claims. (Cl. 200—146)

Our invention relates to an electric circuit breaker and more particularly to a breaker of the fluid jet or impulse type.

An object of our invention is to provide an improved circuit breaker which will be efficient and positive in its interrupting effect throughout the entire range of current rating.

Another object of our invention is to provide a circuit breaker which will operate with an arc duration which is substantially independent of the voltage and current interrupted.

A further object of our invention is to provide a circuit breaker which has a large interrupting capacity and high interrupting speed and which has an operation free of any dangerous overvoltages regardless of the electrical characteristics of the system which is to be interrupted.

We accomplish these and other objects by providing an electric circuit breaker which will interrupt the current in successive phases in an improved and novel manner. The first phase of current interruption takes place between relatively movable contacts by the passage of an arc-interrupting fluid across the arc formed between the relatively movable contacts after an arc of sufficient length has been formed, so that its interruption will take place without danger of restriking. The second phase of current interruption takes place between one of the relatively movable contacts and an auxiliary electrode which is electrically connected to the other of the relatively movable contacts through a resistor. This electrode is also movable into the region between the relatively movable contacts so that when the arc between the contacts is interrupted an arc of much smaller intensity will restrike between one of the contacts and the electrode. An arc-extinguishing fluid is then injected across this second arc to interrupt it.

Further objects and advantages of our invention will become apparent from the following description referring to the accompanying drawing, and the features of novelty which characterize our invention will be pointed out with particularity in the claims annexed to and forming a part of this specification.

In the drawing, Fig. 1 is a side elevation partly in section of a high voltage electric circuit breaker embodying our invention; Figs. 2 and 3 illustrate a portion of the electric circuit breaker illustrated in Fig. 1 in its two successive phases of operation.

Referring to the drawing, in Fig. 1 we have illustrated a high voltage vertical electric circuit breaker of the impulse type which includes rela-

tively movable interrupting contacts 10 and 11. An auxiliary electrode 12 is also provided which is movable into the region between the relatively movable contacts. This auxiliary electrode 12 is electrically connected to the contact 11 through a suitable resistor 13. The auxiliary electrode, which according to our invention is to be moved adjacent the arc path between the relatively movable contacts, may be mounted for movement in any suitable manner. We have found that a particularly efficient structure obtains when the electrode is suitably mounted on a member 14 which surrounds the relatively movable contacts. The member 14 provides an explosion chamber which is substantially closed at one end, it having a bore only sufficiently large at that end to accommodate the contact 10 and to allow relative movement therebetween. The opposite end of the member 14 is open and this open end cooperates in telescoping relation with a relatively stationary cylinder 15. The member 14 therefore acts as an interrupting chamber and also as a plunger piston, since it is mounted for reciprocatory movement. The plunger piston 14 may be moved in any suitable manner and we have found a practically efficient structure obtains when the piston is attached to the movable contact 11.

The actuating mechanism for the movable contact 11 of the relatively movable contacts includes a shaft 16 which carries the contact 11. The shaft 16 is mounted for reciprocatory movement and may be moved by any suitable structure, such as by an operating member 17 and links 18 which are in a pedestal 19. The pedestal 19 also forms a base member on which a hollow cylinder 20 is mounted. A hollow cylinder 21 is in turn mounted on the cylinder 20, the former acting as a housing for my improved circuit breaker.

The circuit breaker may be suitably connected in a line through terminals 22 and 23. The contact 10 may be solidly connected to the terminal 22 and the contact 11 may be electrically connected to the terminal 23 through sliding contacts 24.

Any suitable source of arc-extinguishing fluid may be used, such as a gas under pressure, or a liquid. When a liquid, such as oil is employed, it may be placed in the cylinders 20 and 21 so that my improved electric circuit breaker will be completely immersed in the oil. When a gas is employed, such as air, a source under pressure is piped to the interrupting chamber with a valve

arrangement disposed to be opened when it is desired to extinguish the arc.

The operation of our improved electric circuit breaker is as follows:

When it is desired to interrupt the circuit 22, 23 the actuating member 17 is moved so as to allow the shaft 16 and the movable contact 11 to move away from the contact 10. Upon this movement an arc is formed between the relatively movable contacts as will be seen in Fig. 2. Since the plunger 14 is mounted for movement with the movable contact 11 the plunger will also descend and cause the arc-extinguishing fluid which is in the cylinder 15 to be expelled. In order to provide an arrangement so that the arc between the contacts 10 and 11 will be interrupted only when a sufficient length of arc has been formed, we provide perforations or openings 25 in the side walls of the cylinder 15 in such a plane that the arc-extinguishing fluid may be displaced through these perforations until they are closed by the side walls of the plunger 14. When the perforations or openings 25 have been closed a sufficient length of arc will have formed between the relatively movable contacts so that it may be interrupted without the danger of restriking. When the openings 25 are closed by the side walls of the plunger piston 14 the displaced arc-extinguishing fluid will no longer pass through the perforations but will pass into the interrupting chamber, across the arc between the relatively movable contacts and out through transverse vents 26. A barrier 27 is provided below the vents so as to force the arc-extinguishing fluid to pass transversely of the interrupting chamber and between the relatively movable contacts before it passes out through the vents 26. The barrier 27 may also act as the support for the member 14 on the movable contact 11.

As soon as the current approaches zero the arc is interrupted momentarily at the interrupting contacts by the oil blast. When the recovery voltage appears the arc restrikes to the auxiliary electrode 12 so that the current passes through the resistor 13 connected to the auxiliary electrode 12 and thence to the contact 10. This is because the auxiliary electrode and movable contact will have reached a position, illustrated in Fig. 3. At this time the second phase of the current interruption will take place, since the auxiliary electrode is now moved into the region between the relatively movable contacts. As above described, a second arc will have struck between the auxiliary electrode and the contact 10. However, the intensity of this arc will be much less than was the intensity of the arc which existed between the relatively movable contacts, since the current now passes through the current limiting resistor 13. Thus, regardless of the intensity of the arc-extinguishing fluid jet, no over-voltage need be feared at the moment the arc between the relatively movable contacts is interrupted. Furthermore, the interruption of this arc is facilitated by the fact that when a resistance is inserted in a circuit the speed at which the voltage recovery takes place is considerably lessened.

When our improved electric circuit breaker is in the position illustrated in Fig. 3, vents 28 which are in the side walls of the plunger piston 14 are no longer obstructed by the contact rod 10. Some of the arc-extinguishing fluid will therefore be displaced across the arc between the contact 10 and the auxiliary electrode and out through the transverse vents 26. Since, as above stated,

this latter arc is very weak owing to the effect of the resistor 13 it will be easily extinguished by the arc-extinguishing fluid which finds its way through the region between the contact 10 and the auxiliary electrode to the vents 28. Thus, owing to the slight density of the current which has to be interrupted with the extinguishment of the latter arc and to the damping effect of the resistor 13, this second interruption proceeds with a very small amount of oscillations and without noticeable over-voltages.

It is interesting to note that during the closing of the circuit breaker the resistor 13 acts as an impact resistance and reduces considerably the current in-rush, for instance, in case the circuit breaker is closed on a transformer at no load.

In view of the foregoing it will be seen that we have provided a new and improved high speed circuit breaker for high tension circuits that employs a method which interrupts the current in two successive phases in an improved and effective manner. In the first phase the arc is not interrupted until a sufficiently long arc has been formed so that it may be broken without danger of striking, and in the second phase a reduced current arc is formed between one of the contacts and the auxiliary electrode. This latter arc being relatively weak may be easily broken by the passage of arc-extinguishing fluid across it.

Although we have shown and described particular embodiments of our invention, we do not desire to be limited to the particular embodiments described, and we intend in the appended claims to cover all modifications which do not depart from the spirit and scope of our invention.

What we claim as new and desire to secure by Letters Patent of the United States, is:

1. An electric circuit breaker for high voltage power circuits including relatively movable interrupting contacts, an auxiliary electrode movable adjacent to the arc gap formed between said contacts, a resistor, said resistor being electrically connected between said auxiliary electrode and one of said contacts, actuating means for said relatively movable contacts and said auxiliary electrode, said relative movement of said contacts and said auxiliary electrode causing first, formation of a predetermined length of arc gap and arcing between said interrupting contacts and finally, reduced arcing between said electrode and one of said contacts, and means including an arc-extinguishing fluid for extinguishing in sequence said arcs so that the circuit is completely opened.

2. An electric circuit breaker for high voltage power circuits including relatively movable interrupting contacts, an auxiliary electrode movable adjacent to the arc gap formed between said contacts, a current limiting resistance interconnecting said electrode and the circuit, actuating means for said contacts and said auxiliary electrode, said relative movement of said contacts and said auxiliary electrode causing first, arcing between said interrupting contacts and finally, after predetermined separation of said contacts arcing at reduced current between said electrode and one of said contacts, and means including an arc-extinguishing fluid for causing said arc between said interrupting contacts to be extinguished after a predetermined length of arc has been drawn so that its interruption will take place without danger of restriking and for finally extinguishing said reduced current arc so that the circuit is completely opened.

3. An electric circuit breaker for high voltage power circuits including relatively movable interrupting contacts, an auxiliary electrode movable into the region between said contacts, a resistance interconnecting said electrode and the circuit for limiting current flow through said electrode, actuating means for said contacts and said auxiliary electrode, said relative movement of said contacts and said auxiliary electrode causing first, arcing between said interrupting contacts and second, reduced current arcing between said electrode and one of said contacts after interruption of said first-named arcing, an arc-extinguishing fluid, an insulating piston structure operatively connected to one of said relatively movable contacts and said electrode, and means including said piston structure for causing said fluid to pass over said arc between said interrupting contacts to extinguish it after predetermined separation of said contacts and for causing said fluid to pass over said second mentioned arc and extinguish it.

4. An electric circuit breaker including relatively movable contacts, an auxiliary electrode movable into the region between said movable contacts, actuating means for said contacts and said auxiliary electrode, said relative movement of said contacts and said auxiliary electrode causing arcing between said contacts and between said electrode and one of said contacts, an arc-extinguishing fluid, a movable hollow piston structure having an open end and a plurality of groups of transverse vents, a relatively stationary cylinder of slightly larger diameter than said piston and so constructed and arranged as

10 to receive the open end of said piston, and perforations in said cylinder, said piston structure being movable with said actuating means for causing said fluid to be displaced from said cylinder through said perforations until the arc between said contacts is of a predetermined length at which time said piston walls will substantially close said perforations and allow said fluid to pass over the arc between said contacts to extinguish it and through one of said groups of vents and for causing said fluid to pass over said arc between said electrode and said one of said contacts to extinguish it and through said other of said groups of vents.

15 5. An electric circuit breaker for high voltage power circuits comprising relatively movable interrupting contacts, means for separating said contacts to form an arc gap of predetermined length, means for directing a fluid blast through said gap for extinguishing the power arc, an auxiliary electrode movable in accordance with said contact separating movement to a position adjacent to said arc gap for defining a second arc gap shorter than said first-named arc gap whereby the recovery voltage after arc interruption at said contacts will establish a second arc at said second arc gap, a current limiting resistance interconnecting said electrode and the circuit for decreasing the intensity of said second arc, and means for also directing a fluid blast across said second arc gap for finally interrupting the circuit.
